INVENTOR

Daniel Crowley

United States Patent Office.

DANIEL CROWLEY, OF PHILADELPHIA, PENNSYLVANIA, ASSIGNOR TO
HIMSELF AND J. STANLEY BRUNER.

Letters Patent No. 74,202, dated February 11, 1868.

IMPROVEMENT IN CLEANER FOR DRAWING-ROLLERS.

The Schedule referred to in these Letters Patent and making part of the same.

TO ALL WHOM IT MAY CONCERN:

Be it known that I, DANIEL CROWLEY, of the city and county of Philadelphia, and State of Pennsylvania, have invented an Improved Cleaner for Rolls in Machinery for Working Cotton; and I do hereby declare that the following is a full and exact description thereof, reference being had to the accompanying drawings, making part of this specification.

A single rank of rollers, with the cleaners applied thereto, would sufficiently show my invention, but I have represented a full set of the rollers in the drawings—

Figure 1 being a front elevation of a set of rollers, provided with my improved cleaner.

Figure 2 an end elevation thereof.

Figure 3 an inside view of one of the cleaners.

Like letters designate corresponding parts in all the figures.

Let A A represent the rollers, the upper set cylindrical or smooth, the lower set fluted, between which the roving or yarn passes. It is necessary to keep these rollers clear of dirt, and to prevent the lapping of cotton fibres around them, which otherwise would soon clog them, so as to render them useless, or entirely stop their rotation. It is also desirable to cause these rollers to detach all motes and impurities from the roving or yarn, and thereby improve its quality; and to effect this the rollers must be cleaned as fast as they become foul. The upper or smooth rollers are sometimes varnished, and sometimes covered with leather, to cause the impurities to adhere to them, and become detached from the roving or yarn. Hence the necessity of a thorough cleaner to effect this purpose.

Heretofore cloth cleaners have been used, being kept in light contact with the rollers. But cloth only very imperfectly answers the purposes: first, because it cannot well adapt itself to the surface of the rollers, so as to wipe all parts thereof; second, because its texture is not suitable to brush off and retain the impurities; third, because it becomes glazed over frequently; fourth, because it requires frequent cleaning—four times a day; fifth, because it fails to prevent the lapping of fibres; sixth, because it produces undue friction on the rollers; seventh, because it is costly, and wears out rapidly; and, finally, because it effects the purpose in a very imperfect manner. But, notwithstanding these imperfections, no good substitute has been found before that which is the subject of the present invention.

I employ sheep-pelts, that is, sheep-skins, tanned or "tawed" with the wool on, and applied with the ends of the wool pressing against the rollers. The cleaners B B are made of pieces of this pelt, of sufficient size to properly cover the sets of rollers, and are attached to backs or boards, substantially as shown in the drawings, so as to be held in proper position, and pressed with the proper degree of force against the rollers, the pressure being adjustable if desired. The cleaners are readily removable for the purpose of freeing them of the collected impurities.

The peculiar advantages of cleaners made of this material, are, adaptability to the surface of the rollers, reaching well around them, and cleaning all parts thereof; great elasticity, exceeding durability, capacity to collect and retain the impurities for a comparatively long time, and efficiency in cleaning the rollers. It is also free from the objections to the cloth cleaners, as above set forth, and costs much less. Yarn passed through rollers with these improved cleaners is worth fifteen per cent. more than with cloth cleaners, because being better freed from dirt and impurities.

What I claim as my invention, and desire to secure by Letters Patent, is—

The combination of cleaners B B, constructed as described, with the rollers A A, substantially as and for the purpose herein specified.

DANIEL CROWLEY.
